FRUIT PACKING ACCESSORY

Donald E. Lower, Aspers, Pa., and Michael Paul Roche, Baltimore, Md., assignors of one-fourth to Martha B. Lower, Aspers, Pa., and one-fourth to Mary C. Roche, Baltimore, Md.

Application April 8, 1933, Serial No. 665,172

20 Claims. (Cl. 226—17)

The invention relates to the packing of fruits of various sorts in baskets or the like for convenience and safety in shipment.

It is well known that in the packing of fruit it is a common practice to provide a tray on which is placed the facing layer, usually of prime fruit, which layer is of course intended to be the top one when the basket or other container is opened. Also placed upon this tray is a shell open at both ends and within this shell it is customary to insert a liner of paper, cardboard or other suitable material for the purpose of cushioning the fruit against shocks and jars and consequent bruising during transportation or handling. The shell and liner having been placed in position, the fruit is filled in, and the shell is removed, after which the basket or other container is placed in inverted position over the filled liner. The entire combination is then turned over so that the tray which was previously the bottom will be at the top and this tray is then removed so that the lid or cover may be placed on the container.

A difficulty encountered in this procedure is the necessity for more or less tucking the liner in place within the shell inasmuch as such liners have more or less of a natural tendency to collapse and are consequently difficult to place properly and rapidly against the inside of the shell. Liners of various types are used, some being simply inserted in more or less strip or sheet-like form and then pushed against the shell, the ends being then connected by some appropriate means, all of which is time consuming and annoying. It is with these objections in view that we have devised the present invention which has for its general object the provision of an accessory whereby a preformed liner may be simply and quickly engaged with the supporting tray so that the shell may be readily telescoped onto the liner in proper relation thereto preliminary to filling in the fruit, vegetables or any other similar commodities to be handled.

An important object of the invention is to provide a tray, for supporting the facing layer of fruit, equipped with means about which the liner is initially placed with ease even though the liner may be in a somewhat folded or at least contracted condition, the means carried by the tray being operable to expand the preformed liner to its proper extent and at the same time draw it down into proper engagement or relation with the tray that the necessary shell may, as the next step, be telescoped over the liner in close fitting

relation thereto without, however, it being necessary to press the liner manually into place.

Another object is to provide an accessory of this character which may be lever operated and which will consequently require but the little effort needed to swing the lever.

Another object is to provide a device of this character in which the parts are so constructed and arranged that while the liner will be drawn down properly into cooperative relation to the tray there will be no danger of tearing or otherwise damaging the liner.

A further object is to provide a device of this character which involves remarkably few parts and which will consequently be simple and inexpensive to manufacture, not likely to get out of order, strong, durable, and a general improvement in the art.

To the attainment of the foregoing and other objects and advantages, the invention preferably consists in the details of construction and the arrangement and combination of parts to be hereinafter more fully described and claimed, and illustrated in the accompanying drawing in which:

Figure 1 is a vertical or longitudinal sectional view through the complete assembly constructed in accordance with the invention, the preliminary position of the liner and gripping means therefor being shown by dot and dash lines and the final position being represented by solid lines.

Figure 2 is a plan view of what is shown in Figure 1.

Figure 3 is a perspective view of the tray showing the gripping or expanding means in elevated or initial position.

Figure 4 is a cross section on a larger scale taken on the line 4—4 of Figure 2.

Figure 5 is a cross section taken on the line 5—5 of Figure 4 and illustrating the character of the liner.

Figure 6 is a perspective view of a basket filled by the apparatus disclosed.

Figure 7 is a cross section showing a modified form of the device.

Figure 8 is a fragmentary perspective view showing the link and yoke mechanism of the modified form, and

Figure 9 is a detail perspective view of one of the links alone.

Referring more particularly to the drawing it will be observed that the accessory comprises, in the first place, a supporting base or tray structure indicated as a whole by the numeral 10 and here shown as comprising an outer ring member.

11 which while it might be any one of selected shapes is conveniently of inverted L-shape in cross section with the edge of its upper flange directly outwardly and rolled or beaded at 12 for the sake of stiffness, an having the lower edge of its vertical flange braced as by a hoop 13 about which it is rolled. Suitably secured, as by welding or other means, within the confines of this ring 11 is a concavo-convex tray 14 upon which 15 is to be placed the facing layer of fruit and which of course serves to support as a consequence all of the fruit being packed into a given receptacle. To facilitate the proper positioning of the facing layer and to prevent the fruit or other articles 20 from rolling about or becoming otherwise displaced, it is preferable to provide a stop or guide 15 which may simply be a short length of angle bar riveted or otherwise secured upon the top surface of the tray 14 at one edge thereof and extending radially.

20 The horizontal flange of the ring 11 serves as means for supporting the liner and shell to be described and for retaining these elements in proper relation to the base there is provided an upper standing ring 16 secured to the ring 11, substantially one half of this ring 16 being cut away or reduced in height and thickness as very clearly shown at 17 in Figure 3, and the adjacent end portions of the uncutaway part being likewise reduced in thickness so as to define ears 18.

30 The collar or ring 16 is intended for telescopically receiving the lower end of a liner 19 engaged exteriorly thereupon. In accordance with our invention it is intended that this liner be pre-formed, that is to say that it be initially prepared so as to be of an appropriate size to fit within the shell 20 which is in turn telescoped on to it. As this liner is intended to serve as a protection for the fruit, vegetables or the like so as to prevent them from becoming bruised, it is highly preferable that the liner be constructed in corrugated form as such will be sufficiently yielding to prevent damage to the fruit when the cover of the receptacle is clamped down or secured tightly and during transportation or handling. 45 Moreover a corrugated type of material will permit a limited expansion so as to avoid tearing when the liner is drawn down snugly into cooperative relation to the supporting base or tray assembly.

50 The means for gripping, expanding and drawing down the liner, of course prior to engagement of the shell thereabout, is represented in the first form of the invention, shown in Figures 1 to 4, as comprising a substantially semicircular yoke 21 which has its ends pivoted at 22 upon the ears 18 and which has its intermediate portion carrying a handle or lever 23 for manipulating purposes. Moreover this lever 23 has its intermediate portion preferably bent as at 24 to provide a catch or latch adapted to snap or frictionally engage beneath the rolled edge 12 of the horizontal flange of the base ring 11.

55 The use of the device is as follows: The fruit to be displayed at what will eventually be the top of the container or receptacle used is first packed as a single layer in the desired arrangement upon the tray 14, the guide or stop 15 facilitating this operation. With the yoke 21 in elevated position as shown by dot and dash lines in Figure 1, or by 60 full lines in Figure 3, the operator takes the liner 19 which is probably originally folded, and opens it up sufficiently that one part of the lower edge thereof may be engaged about the uncutaway portion of the ring 16 and so that the diametrically opposite portion may be engaged exteriorly about

the yoke 21. When the handle or lever 23 is then depressed the downward swinging movement of the yoke 21 upon its pivots 22 will, owing to the frictional engagement of the yoke with the liner, pull the latter downwardly toward the base 10 and at the same time cause the liner to expand properly so that it will telescope completely about the entire ring 16 and the yoke 21. In view of the fact that when the lever 23 is in its lowermost position the kinked latch portion 24 thereof 10 engages over the rolled edge 12 it is quite apparent that the yoke 21, and consequently the liner, cannot spring up from any cause and permit the liner to collapse. In view of the fact that the yoke 21, which is of less thickness than the ring 16, occupies the portion of the latter which is cut away in thickness it is clear that the assembled ring and yoke will form a complete and true circle and will maintain the liner in similar shape which, in actual practice, is generally frusto-conical. The liner having thus been expanded and drawn down, the shell 20 is placed about it to hold it in shape and prevent it from bursting, after which the remainder of the fruit to be placed within a container is filled into the space 20 within the liner, and the shell is removed.

As the next step, the container which may be a basket of conventional type as shown at 25 in Figure 6, is inverted and placed over and about the liner. After this, the entire assembly should then be inverted or turned upside down and the base, which is then of course located at the top of the basket, is pulled away, leaving the liner 19 in position between the fruit or other articles and the basket. The filled container will then have the appearance shown in Figure 6 and will be in condition to have the lid or cover applied and secured.

As a modification of the extremely simple general scheme above described, recourse may be had to the alternative construction illustrated in Figures 7 to 9 which differs from the first form in that it may be considered an added development of the basic idea and an advance in efficiency without, however, sacrificing simplicity and ease 40 of operation. In this modified form we provide a movable yoke or expanding member arrangement involving a combination of rectilinear and swinging movements so as to obtain a more positive expanding action on the liner. This is accomplished 50 by providing what may be considered a jointed yoke instead of the simple semicircular yoke of the first described form.

55 In detail, this modification involves the provision of the same base structure previously described, equipped with the same concavo-convex facing layer supporting tray and in fact possessing substantially the same detailed construction. However, in this form, the upstanding collar or ring 16 has pivoted to its diametrically opposite ears 18, as shown at 27, links 28 to which are in turn pivoted, at 29, the ends of an arcuate yoke 30 equipped with a handle 31 similar to the above described handle or hand lever 23. In the initial position, that is to say when the parts are ready 65 to have the liner applied, the links 28 extend vertically and lie against the abutment shoulders 32 defined by reducing the thickness of the ring or collar 16. In this alternative form it is intended that the liner be expanded by a longitudinal pull upon the handle 31 which will cause the yoke 30 to move outwardly and then downwardly, the links 28 of course swinging downwardly so as to lie against the outside of the cut away or reduced portion of the collar 16, the yoke 30 com- 75

ing down onto the supporting flange 12 of the base structure and into surrounding relation to the collar, as in the first form. The details as to the exact relative thickness or cutting away of the 5 collar, links and yoke might be varied, but the upper ends of the links 28 are shown as bifurcated at 33 for the reception of the ends of the yoke 30, as will be apparent from an inspection of Figures 7, 8, and 9, the idea being that there will be a 10 slight clearance between the yoke and collar to facilitate passage of the yoke over the edge of the collar without danger of catching. When the yoke and links are in lowered position they will form continuations of one another so that there 15 will be defined a substantially unbroken or true circle.

This form of the device is used in the same manner as the first form, one portion of the liner being engaged with the uncutaway portion of the 20 collar 16 and the opposite portion of the liner being engaged against the outside of the curved yoke 30. In view of the fact that the links 28 extend vertically initially it is clear that they will be located within the confines of the liner so 25 that there will be no danger of the liner catching on them, it being therefore unnecessary for the operator to press out or in any way touch the liner to guide it into place. The liner having been thus placed in its initial position, the operator grasps the handle 31 and pulls upon it 30 whereupon the yoke 30 will move outwardly in a rectilinear direction and apply expanding pressure to the liner. Thereafter, the outward rectilinear movement of the yoke causes it as well as the links 28 to move downwardly, the frictional 35 drag against the inner surface of the liner causing it to be brought down into its final position in snug telescoping relation upon the collar. It is preferable that the pivots 27 and 29 be out of 40 vertical alignment as shown so as to obtain the proper sequence of relative movement of the yoke 30 and links 28 to bring about the smoothest and most efficient action, that is to say, so that the yoke will move outwardly to expand the liner 45 partially before it moves downwardly to seat it about the collar.

The principle involved in both forms and still others which might be conceived of, is of course the same and the utility is identically the same in 50 both or still other possible instances, the only differences being a mere matter of mechanical construction of details of the operating means. It will be clear from an inspection of the drawing taken in conjunction with the foregoing description 55 that we have provided a very simple device by means of which the work of packing fruit and other commodities of a more or less perishable nature may be greatly lessened, there being a manifest decrease in the length of time required 60 and the effort and skill involved so that the work may be carried on at less cost.

From the above it is believed that the construction, operation and advantages will be readily apparent to one skilled in the art without further 65 explanation.

While we have shown and described preferred embodiments of the invention, it should be understood that the disclosure is merely an exemplification of the principles involved as the right is 70 reserved to make all such changes in the details of construction as will widen the field of utility and increase the adaptability of the device provided such changes constitute no departure from the spirit of the invention or the scope of the 75 claims hereunto appended.

Having thus described the invention, we claim:

1. In a fruit and vegetable packing device, the combination of a supporting base having an upstanding collar, movable means carried by said base adapted to engage a flexible liner disposed about the collar, and means for moving said means to expand the liner and draw the same down into telescoping relation to the collar. 5

2. In a fruit packing device, a supporting base having an upstanding collar and further having 10 an outstanding flange adapted to support a shell, means movably mounted on the base adapted to engage within a flexible liner, and means for moving said means to expand the same and draw it down about the collar and against the flange so 15 that the liner will be capable of telescopically receiving said shell.

3. A fruit packing device comprising a supporting base having an upstanding collar and an outstanding supporting portion, means swingably 20 mounted on the base and adapted to have a liner engaged exteriorly thereagainst, and means for swinging said movable means to expand the liner and draw the same down in surrounding relation to the collar. 25

4. A fruit packing accessory comprising a supporting base including a tray and having an upstanding collar adapted to receive a shell thereabout, a member swingably carried by the base above the tray thereof adapted to engage a flexible liner disposable thereabout and about the collar, and means for moving said swingable member to expand and frictionally drag down the liner into embracing relation to the collar. 30

5. In a fruit packing apparatus, a supporting 35 base including a tray and an upstanding collar, an arm member pivoted upon the collar above the tray adapted to engage a liner disposable exteriorly thereagainst and upon the collar, and means for swinging the arm member outwardly 40 and downwardly for expanding the liner and carrying it to a position entirely telescoping the collar.

6. In a fruit packing apparatus, a supporting 45 base including a tray and an upstanding collar, an arm member pivoted upon the collar above the tray adapted to engage a liner disposable exteriorly thereupon and upon the collar, means for swinging the arm member outwardly and downwardly for expanding the liner and carrying it 50 to a position entirely telescoping the collar, and latch means for holding said arm in lowered position.

7. In a fruit packing apparatus, a supporting 55 base structure including a tray and an upstanding collar concentric with the tray, and means pivotally connected with the base structure and adapted to engage interiorly of a liner for frictionally gripping the same and drawing it down 60 in embracing relation to said collar. 60

8. In a fruit packing apparatus, a supporting 65 base structure including a tray and an upstanding collar concentric with the tray, and means pivotally connected with the base structure and adapted to engage interiorly of a liner for frictionally gripping the same and drawing it down in 70 embracing relation to said collar, lever means operatively connected with said pivoted means for moving the same.

9. In a fruit packing apparatus, a supporting 75 base structure including a tray and an upstanding collar concentric with the tray, and means pivotally connected with the base structure and adapted to engage interiorly of a liner for frictionally gripping the same and drawing it down in 75

- embracing relation to said collar, lever means operatively connected with said pivoted means for moving the same, and means on the lever means cooperating with the base structure for retaining 5 said pivoted means in downwardly swung position within the confines of the liner.
10. A fruit packing appliance comprising a base structure having an outstanding supporting flange and an upstanding collar, a tray located with- 10 in the confines of and below the collar, and mechanical means for drawing a liner down onto said flange and about said collar.
11. A fruit packing appliance comprising a base structure having an outstanding supporting flange 15 and an upstanding collar, a tray located within the confines of and below the collar, mechanical means for positioning a liner about said collar with its lower edge upon said flange, said means comprising a curved arm member pivoted at its 20 ends upon the collar and disposable against the inside of a liner, and means connected with said curved arm for swinging the same downwardly and causing it to frictionally drag the liner into telescoping relation about the collar.
25. 12. A fruit packing appliance comprising a sup- porting base structure having an outstanding flange and an upstanding collar, a dished tray located within the confines of and below the collar, a curved arm disposable in concentric rela- 30 tion to a portion of the collar and having its ends pivoted thereto, said arm being adapted to engage within a liner initially engageable exteriorly upon and against the opposite portion of the collar, and means for swinging the arm down- 35 wardly for frictionally engaging, expanding and dragging down the liner into encircling relation to the collar with its edge at said flange.
13. A fruit packing device comprising a sup- porting base structure including a tray and an 40 upstanding collar, a curved yoke having the ends of its arms movably connected with the collar and adapted to have a liner engageable against the outside thereof, the liner also engaging against the outside of the opposite portion of the collar, 45 said yoke having a combination of outward rectilinear and downward swinging movement to exert expanding action upon the liner and to frictionally grip the same and draw it down about the collar.
50. 14. A fruit packing accessory comprising a sup- porting base structure including a tray, and a collar located in concentric relation to the tray, links pivotally connected with the collar and

swingable from vertical to horizontal position, and a curved yoke having the ends of its arms pivoted to said links, said yoke and the opposite portion of the collar being adapted to be engaged by the lower end of a flexible liner, and said 5 yoke being movable radially outwardly and swingable together with said links downwardly for expanding the liner and frictionally dragging it down into position about the collar.

15. A packing appliance comprising a base hav- 10 ing a guide portion thereon adapted to have a liner disposed thereagainst, and means down- wardly swingably and rectilinearly movably mounted on the base and engageable with the interior of the liner for holding the latter taut 15 upon the base.

16. A packing accessory comprising a base adapted to support a liner, and means movably mounted on the base and engageable with the interior of the liner for holding the same said 20 means having a combined downwardly swingable and rectilinear movement.

17. A packing accessory comprising a support- 25 ing tray adapted to have a liner disposed there- upon, and means movably mounted on the tray for gripping, expanding and drawing down the liner thereonto.

18. A packing appliance comprising a support having an upstanding portion thereon adapted to have a liner telescoped thereonto, and means 30 located within the confines of the liner and swing- able downwardly to engage the interior thereof for drawing the liner down onto the support and into closely embracing relation to the upstand- 35 ing portion.

19. A packing appliance comprising a sup- port having an upstanding guide thereon adapt- 40 ed to have a liner telescopically engaged there- with, and means movably carried by the support and swingable downwardly and outwardly with respect to the liner for drawing the same down into engagement with the support and the guide.

20. A packing appliance comprising a support having a guide thereon adapted to be telescopi- 45 cally engaged by a liner, means pivotally support- ed with respect to the support and movable in an arcuate path toward the support for frictional engagement with the interior surface of the liner for drawing the same down onto the support, and means for holding said means against movement. 50
